UNITED STATES PATENT OFFICE

HANS MARTINIUS RIIS, OF OSLO, NORWAY

PROPELLER

Application filed May 1, 1931, Serial No. 534,351, and in Norway May 7, 1930.

The present invention relates to propellers for ships and air craft and the object of the invention is to provide a propeller so constructed that an even pressure is obtained at 5 the entire pressure side of the propeller wing and that the slip becomes minimized.

The invention will be fully described in connection with the annexed drawings where:

Fig. 1 diagrammatically illustrates the construction of a propeller wing as seen from 10 the side thereof.

Fig. 2 illustrates the same in plan view and Fig. 3 the same as seen from the end.

Figs. 4 and 5 illustrate diagrammatically 15 the calculation of the exit angle of the pressure side.

Fig. 6 is a view similar to Fig. 1 illustrating a modified form of construction.

Fig. 7 illustrates a pattern adapted to be 20 used when making a model of the wing, and

Fig. 8 shows a ready propeller with three wings seen from the rear thereof.

According to the present invention the propeller is designed and calculated starting 25 from the rear edge of the wings which edges in all cases are perpendicular to the propeller axis.

At first is drawn the propeller axis $m-n$ and a line $r-s$ perpendicular thereto, which 30 latter indicates the rear edge of a propeller wing. The place o where these lines intersect becomes the centre of spherical surfaces on which the profile of the pressure side of the wing shall be laid. The rear edge of the 35 propeller thus will lie in a section through an imaginary sphere the diameter of which is like the diameter of the propeller.

The diameter $0-1$ of the propeller hub is now chosen and the circle portion $l-c$ is 40 drawn. Then are, preferably with equal distances therebetween, drawn a number of similar circle portions from the places $2-7$, as shown, o always forming the center. The distance between the circles is chosen at will, 45 but the smaller said distance is the more correct the shape of the propeller will become.

The spherical surfaces represented by the circles $1-7$ are then intersected by a series of 50 lines parallel to the line $r-s$ and indicating sections $a-f$ through the propeller wing.

The distance between the lines $a-f$ is chosen at will, but also here the correctness of the wing obtained will be greater the shorter said distance is chosen.

Now there is chosen an exit angle for the tangent to the pressure face at the rear edge of the wing at point 1, and this angle forms the figure from which the entire calculation and construction is derived. Said angle is chosen relatively great for propellers which shall run fast and smaller for propellers running with less turns per time unit.

The corresponding angles for the other spheres 2-7 decrease with the distance from the axis $m-n$. However, they do not decrease proportionally with said distance. I have namely found that said angles should always correspond to the formula

$$tg\alpha = \sqrt{\frac{x}{R}}$$

55

60

65

70

75

where R is the distance from the axis $m-n$ and x is an expression which may be expressed by the formula

$$x = R_1(tg\alpha_1)^2$$

where R_1 is the radius of the hub or the distance from the axis to the first sphere and α_1 is the angle chosen at said sphere.

If the angle α_1 is chosen to be 60° the angles, 80 say at the points 3, 5 and 7 then will be 45° , $37^\circ 40'$ and $33^\circ 10'$, as indicated in Fig. 4.

After the angles thus having been determined at the rear edge of the wing for the several spheres are helices laid along the 85 spheres the pitch or angle increasing with increasing distance from the axis $m-n$.

For sake of simplicity only one of these helices shall be described, namely the helice z_3 on the sphere 3 where the exit angle is 45° . 90

The distance between the section lines $a-f$ may be called y . From Figs. 4 and 5 will be seen that the point where the line z_3 intersects the line a lies at a distance k_a from a plane through the rear edge of the wing, that is 95

$$k_a = \frac{y}{tg\alpha_3}$$

k_a now may be considered to be a chord in 100

a circle the radius r_s of which is like the distance from the axis $m-n$ to the point where the sphere 3 and the plane a intersect. The central angle β_s of said chord is determined by the equation

$$\sin \beta_s = \frac{k}{r_s}$$

If a great circle is laid through the point of intersection between z_s and a (see Fig. 5) it will be understood that the chord decreases for the several section planes, and the general formula of the chord will be $r_s \cdot \sin \beta_s$.

If on the sphere 3 there is laid a number of great circles from the rear edge of the wing and forwardly (see Fig. 2) with an angle therebetween corresponding to β_s , the line z_s will pass through the intersections between said great circles and the section planes $a-f$. Thus the pitch will increase towards the front edge of the wing.

The several profile lines which may be thus obtained are shown in projections at Figs. 1-3.

In the embodiment of the propeller here aimed at a cylindrical hub is to be used. The profile of the wings pressure side is passed on to this cylinder by tracing circles with o as centre which pass through the intersection between the hub (dotted line in Fig. 1) and the several planes $a-f$. After the radii of said circles (or spheres) having been calculated by means of the formula

$$R = \sqrt{R_1^2 + Yn^2}$$

where R_1 is the radius of the hub Yn is the distance of the plane from $r-s$, the exit angle for each sphere is determined by means of the previously disclosed formula, whereby the points where the helices intersect the hub cylinder may be calculated or designed.

In the embodiment now described the pressure sides of the wings are formed along lines lying on spheres having a common center in the propeller axis. I have, however, found that the pressure sides of the propeller wings may also with good result be laid along lines on spheres the centres of which do not correspond, but are situated in a plane through the rear edge of the wings.

The calculation and construction of the propeller wings is then effected in practically the same manner as described above, only with the difference, that several circles are drawn the centres of which lie on the line $r-s$ and the radius of which always is

$$Rb = \frac{(\operatorname{tg}^2 \alpha_1 \cdot R_1)}{2} + R_1$$

where R_1 is the radius of the hub (0-1) and α_1 the exit angle chosen at the point 1 (see Fig. 6). The distance between the centres of such circles is preferably always the same, as indicated in Fig. 6.

However, the angles at the several spheres

2-7 in this case decrease in accordance with another formula than disclosed above. In the latter case the exit angle shall in all distances from the axis $m-n$ correspond to the formula

$$\operatorname{tg} \alpha = \sqrt{\frac{x_1 \div R}{R}}$$

where R is the distance from the axis and x_1 is an expression expressed by the equation

$$x_1 = (\operatorname{tg}^2 \alpha_1 \cdot R_1) + R_1$$

where R_1 is the radius of the hub (0-1) and α_1 the exit angle chosen at this point.

I have also invented a special method of preparing models to be used in the casting of propellers according to my invention. Such model is made up of plates the thickness of which is like the distance y between the planes $a-f$. On these plates are, by means of models marked off the points for the lines z in correct distances from the plane through the rear edge of the propeller, whereupon the surface of the wing is formed in accordance with these points.

In Fig. 3 is shown such a model plate for the section plane c in Fig. 1. At said plate is drawn up the line $r-s$ and then the hub, as shown. Then are drawn circles c_2-c_7 , with radii corresponding to the points in the plane c where the latter is intersected by the spheres 2-7. Then from Fig. 2 are measured, on the same circles c_2-c_7 , the corresponding chord lengths from the line $r-s$, which lengths are marked off on the circles on the plate. By drawing a line through the points thus obtained the profile of the pressure side of the wing in the plane c is obtained.

This plate is laid on the top of the third plate and under the fourth plate and marked off thereon. When all plates thus are marked off and formed in accordance with the markings and are assembled so that all lines $r-s$ coincide, the pressure surface is obtained with correct shape.

The thickness of the wings is chosen in accordance with usual calculation of strength, &c., and the suction side is given the profile most corresponding to the profile of the pressure side.

Having now particularly described and ascertained the nature of my said invention and in what manner the same is to be performed I declare that what I claim is:

1. A propeller in which the pressure side of the wings are shaped along lines forming helices on spheres.

2. A propeller according to claim 1 in which the centers of the spheres are situated in a plane lying at right angles to the propeller axis.

3. A propeller according to claim 1 in which the centers of the spheres are situated in a plane lying at right angles to the pro-

steller axis and the rear edge of the wings coincide with said plane.

4. A propeller according to claim 1, in which the spheres have different radii and a common centre in the propeller axis.

5. A propeller according to claim 1 in which the spheres have like radii.

6. A propeller according to claim 1 in which the angle between a tangent to the rear part of the pressure side and the plane of rotation along the rear edge of the wing decreases with the distance from the propeller axis.

7. A propeller according to claim 1 in which the spheres have different radii and the angle between a tangent to the rear part of the pressure side and the plane of rotation at any distance from the propeller axis corresponds to the formula

$$\operatorname{tg}\alpha = \sqrt{\frac{z}{R}}$$

where R is the distance from the axis and α is a constant defined by the equation

$$\alpha = R_1 (\operatorname{tg}\alpha_1)_2$$

where R_1 is the radius of the hub and α_1 is the angle chosen at that point.

8. A propeller according to claim 1 in which the pitch of the helice increases from the rear to the front edge of the wing.

9. A propeller according to claim 1, in which the pitch of the helice increases proportionally to the decrease of the distance of the line from the propeller axis.

10. A propeller according to claim 1 in which the spheres have like radii and the angle between a tangent to the rear part of the pressure side and the plane of rotation at any distance from the propeller axis corresponds with the formula

$$\operatorname{tg}\alpha = \sqrt{\frac{z-R}{R}}$$

11. where R is the distance from said axis and α is an expression defined by the equation

$$\alpha = (\operatorname{tg}^2 \alpha_1 \cdot R_1) + R_1$$

12. where R is the radius of the hub and α_1 is the angle chosen at this point.

In testimony whereof I affix my signature.

HANS MARTINIUS RIIS.
